UNITED STATES PATENT OFFICE.

HUGH McNIFF AND HAROLD E. THOMPSON, OF DENVER, COLORADO.

ROTARY PUMP.

Application filed March 7, 1925. Serial No. 13,736.

To all whom it may concern:

Be it known that we, HUGH McNIFF and HAROLD E. THOMPSON, citizens of the United States, residing at Denver, in the city and county of Denver and State of Colorado, have invented certain new and useful Improvements in Rotary Pumps; and we do declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to improvements in pumps and has reference more particularly to rotary pumps of the type in which centrifugal force is employed for the purpose of causing the water to flow.

In places where large quantities of water must be raised from one level to another, as, for example, in irrigating land, it is desirable to have a pump that is as simple as possible, which can be manufactured at a comparatively low price, and which cannot be readily gotten out of order.

It is the object of this invention to produce a pump that shall be of extremely simple construction; that will have a large capacity, and that will be capable of pumping water mixed with dirt, sand, gravel and even small rocks.

The above objects are attained by means of a construction which, briefly described, comprises a vertical shaft mounted for rotation about its axis. Secured in spaced relation about the shaft are a plurality of pipes whose lower ends terminate quite close to the shaft, but whose axes diverge upwardly so that when the shaft and pipes rotate, the locus of the axes of the pipes form the outer surface of an inverted, truncated cone. When the lower ends of the pipes are immersed in water while rotation takes place, the centrifugal force will cause the water to flow upwardly through the inclined pipes in a manner readily apparent and well understood.

Our invention can be most clearly described and will be most readily understood when reference is had to the accompanying drawing, in which the preferred embodiment thereof is shown, and in which:

Fig. 1 is a vertical section through a well, taken on line 1—1, Fig. 2, showing our pump

in place therein, portions of the pump being broken away to better show the construction;

Fig. 2 is a top plan view of the pump;

Fig. 3 is a view showing one of the pipes with parts thereof broken away; and

Fig. 4 is a vertical section through the bearings of the shaft.

Numeral 1 designates a well, which, from a theoretical standpoint, may be of any depth, but which, for practical reasons, must be comparatively shallow. About the well, on the surface of the ground, we provide a frame 2 which may be made of wooden planks, as shown, or of metal plates, or of any other suitable material including concrete. A bearing spider having four arms 3 are fastened to suitable standards 4, which are secured to the frame 2 by means such as bolts 5. At the point of juncture of the arms 3, we have provided an opening 6 for the reception of the vertical shaft 7. The lower portion of the opening 6 is provided with an enlargement 8 for the reception of a conventional ball-bearing 9 that is held in place by a threaded ring 10. A pulley 11 is secured to the upper end of the shaft 7. Between the lower side of the pulley and the upper surface of the bearing spider, we provide a thrust bearing 12 (Fig. 4) upon which the weight of the shaft and associated parts are carried. At the bottom of the well, we provide a second bearing which has been designated by the numeral 13. This bearing has a ball-bearing 14 similar to the upper ball-bearing 9, held in place by a threaded ring 15 corresponding to ring 10. The lower bearing may be provided with legs 16, which rest upon the bottom of the well in the manner shown. Two or more plates 17 are secured to the legs 16 in the manner shown in Fig. 1. The purpose of plates 17 will presently appear. Secured to the shaft 7 in such a manner that they cannot rotate with respect thereto are disks 18 and 19. The lower disk, indicated by the numeral 18, is smaller in diameter than the upper disk. Each disk has an equal number of holes spaced equiangularly about the shaft 7. The distance from the center of the disk 18 to the center of the holes therein is less than the corresponding distance in disk 19. Pipes 20 project through corresponding holes in the two disks and are welded to the disks or otherwise prevented from rotating about their own axis. The lower ends of the pipes are bent forwardly in the direction of

105

110

rotation and are somewhat flared or bell-shaped, as indicated by the numeral 21. The upper ends of the pipes are bent outwardly and downwardly at points 22 and 23, respectively. An annular tank 24 is supported on suitable brackets 25 secured to the uprights 4 (Fig. 1). The upper edge of the outer wall of the tank is bent inwardly, as indicated by numeral 26, to provide a flange which prevents the water from splashing out when the pump is operating. A spout 27 opens outwardly from the tank and permits the water to flow out into any suitable conduit.

15 A metal sheet 28 is preferably secured to the disks 18 and 19 so as to provide a smooth outer surface, although this may be dispensed with. A motor 29, which may be an electric motor, a gas engine or any other suitable source of power, is operatively connected to the pulley 11 by means of a belt 30. Within the pipes 20 we prefer to place helical strips 31 of metal which cause the water to travel in a spiral path as it flows upwardly. 25 For reasons which we do not fully understand, the strips 31 appear to increase the efficiency of the pumps. Let us now assume that the well is filled with water to the line 32 and that the shaft 7 with attached disks and pipes is rotated in the direction of the arrows in Fig. 1. The water will normally fill the pipes 20 to the level of the water in the well. When the shaft 7 is rotated, the reaction between the water and the ends 21 will produce a pressure that will cause the water within the pipes to rise somewhat above the level 32. The rotation of the pipes will produce a centrifugal force which causes the water within the pipes to press outwardly against the pipes. This pressure will resolve itself into a radial and a vertical component and the latter, when it exceeds the opposing force of gravity, will cause the water to flow upwardly.

45 The water will soon reach the parts 22 where the centrifugal force will be greatly increased and this will be augmented by the centrifugal force of the water in the down-turned ends 23. All of these forces combine to make the water flow upwardly from the well to the annular tank.

When the lift is great, the speed of rotation must be greater than with a lower lift or else the angle between the axes of the pipes and the axis of rotation must be increased. The blades 17 tend to hold the water against assuming a rotary motion within the well.

55 From the above, it will be apparent that we have produced a pump of simple construction that will raise large quantities of water. The water may be clean or it may have sand and gravel in suspension without

in the least interfering with the operation. 65

Having now described our invention, what we claim as new, is:

1. A pump comprising, in combination, a shaft mounted with its axis substantially perpendicular and adapted to be rotated, a bearing for the lower end of said shaft, a second bearing for the upper end of the shaft, means for rotating the shaft, a plurality of equidistantly spaced pipes secured to the shaft so as to be rotated therewith, the lower ends of said pipes being closer to the axis of rotation than the upper ends, whereby any water that may be in the pipes will be subjected to a centrifugal force, one component of which will tend to make it flow 80 upwardly, and means within said pipes for making the water travel in a spiral path within the pipes.

2. A pump comprising, in combination, a shaft mounted with its axis substantially perpendicular and adapted to be rotated, a bearing for the lower end of said shaft, a second bearing for the upper end of the shaft, means for rotating the shaft, a plurality of equidistantly spaced pipes secured to the shaft so as to be rotated therewith, the lower ends of said pipes being closer to the axis of rotation than the upper ends, whereby any water that may be in the pipes will be subjected to a centrifugal force, one component of which will tend to make it flow 90 upwardly, a spiral strip within said pipes for making the water travel in a spiral path within the pipes, and a number of stationary vanes surrounding the lower ends of said 100 pipes.

3. A pump comprising, in combination, a shaft mounted with its axis substantially perpendicular and adapted to be rotated, a bearing for the lower end of said shaft, a second bearing for the upper end of the shaft, means for rotating the shaft, a plurality of equidistantly spaced pipes secured to the shaft so as to be rotated therewith, the lower ends of said pipes being closer to the 105 axis of rotation than the upper ends, whereby any water that may be in the pipes will be subjected to a centrifugal force, one component of which will tend to make it flow upwardly, means comprising a spiral strip 115 located within said pipes for making the water travel in a spiral path within the pipes, and a number of stationary vanes surrounding the lower ends of said pipes, the lower ends being bent so as to open in the direction in which they rotate while the upper ends are bent outwardly and rearwardly. 120

In testimony whereof we affix our signatures.

HUGH McNIFF.
HAROLD E. THOMPSON.
